D. H. DEERY

LAMP STRUCTURE

Filed June 19, 1923

UNITED STATES PATENT OFFICE.

DANIEL H. DEERY, OF BRIDGEPORT, CONNECTICUT, ASSIGNOR TO THE D. & H. LAMP CO., OF BRIDGEPORT, CONNECTICUT, A COPARTNERSHIP COMPOSED OF DANIEL H. DEERY AND WILLIAM HENNESSEY.

LAMP STRUCTURE.

Application filed June 19, 1923. Serial No. 646,356.

To all whom it may concern:

Be it known that I, DANIEL H. DEERY, a citizen of the United States, and a resident of the city of Bridgeport, in the county of 5 Fairfield and State of Connecticut, have invented certain new and useful Improvements in Lamp Structures, of which the following is a specification.

The present invention relates to an improved lamp structure, particularly a tail-light for automobiles, and has for an object 10 to provide a device of this character which will produce a clear light at the rear of the automobile, and will at the same time 15 brightly and effectually illuminate the number plate, so that the same will be distinctly visible at a relatively great distance.

Another object is to so relate the lamp and 20 the number plate support, forming a part thereof, that the light rays will be directed downwardly upon the plate, so that its entire surface will be clearly and uniformly lighted.

A further object is to provide a structure 25 which will withstand constant vibration and shock, without danger of fracture or loosening, and which will furthermore be moisture and dust proof.

A still further object is to provide a construction in which the glass structure will 30 be cushioned and protected against breakage, and which will permit of the lens being removed, for the purpose of renewal of the lamp bulb, with facility and without the need of tools, and as readily reassembled.

With the above and other objects in view, 35 an embodiment of the invention is shown in the accompanying drawings, and this embodiment will be hereinafter more fully described with reference thereto, and the invention will be finally pointed out in the claims.

In the drawings:

Fig. 1 is a perspective view of the lamp 40 structure, according to the present embodiment of the invention;

Fig. 2 is an extended perspective view of the same, and showing the parts thereof in separated relation;

Fig. 3 is a vertical longitudinal sectional view;

Fig. 4 is a vertical transverse sectional view, taken on the line 4—4 of Fig. 3;

Fig. 5 is a horizontal sectional view, taken on the line 5—5 of Fig. 3; and

Fig. 6 is a perspective view of the spring member employed.

Similar reference characters indicate corresponding parts throughout the several figures.

Referring to the drawings, the lamp structure, according to the present embodiment of the invention, comprises a back or mounting plate 10, having its upper portion rounded to partially conform to a circle, 65 and its lower marginal portion 11 extended an equal distance each side from the center and bent forwardly at a slight angle. Longitudinal slots 12 are provided in each end of the portion 11 for the purpose of receiving the fastening bolts of the number plate, as indicated in dotted lines in Fig. 1, the number plate being at a slight forward angle to the plate 10, whereby to be more effectually illuminated by the lamp, and as 70 will hereinafter more fully appear. A pair of holes 13 are provided in the plate 10 to enable it to be attached by rivets or bolts to the rear lamp bracket of an automobile.

Upon the upper portion of the plate 10 there is mounted a cup-shaped cylindrical lamp casing 14, formed of sheet metal, and having its base portion secured to the plate 10 by a plurality of rivets 15, and provided in the lower half of its cylindrical wall 85 with a parallel-sided opening 16.

A lamp socket 17 is mounted in the casing, being secured in an opening 18 formed in the base of the casing and the plate 10, by soldering or the like, or preferably by 90 peening the edge of the opening 18 into tight relation with the socket, as at 19, Fig. 3. The socket is preferably disposed midway between the axial center of the casing and its lower extremity, and terminates substantially in a central plane through the opening 16. A lamp bulb 20 is fitted therein by means of a bayonet connection 21, and at its

outer projecting end the socket is adapted to have conductor wires connected thereto.

A glass cylinder 22 is fitted within the casing, to form a transparent closure for the opening 16, and also, as will presently appear, to tightly and yieldably secure the colored tail-light lens. Between the inner edge of the cylinder 22 and the base of the casing there is interposed a rubber-ring 5 washer 23, and a leaf-spring member 24, having its intermediate portion bowed, and its end portions 25 bent forwardly therefrom and resting upon the rubber ring, the lines upon which the portions 25 are bent 10 being substantially circumferential and concentric to the cylinder wall. The inner edge of the glass cylinder bears down upon the ends of the spring to tension it, and upon the portions of the rubber ring washer not engaged by the spring ends, the washer being compressed beneath the spring, so that the edge of the cylinder is substantially in contact with a continuous resilient structure 15 formed by the spring and washer.

The forward edge of the glass cylinder projects slightly with relation to the forward edge of the casing, and has seated thereon a rubber-ring washer 26, interposed between the cylinder and the convex-faced 20 colored tail-light lens 27. The lens is secured in place by a rim 28, having a flange 29 bent over upon the lens, and slidably engaged upon the outer surface of the casing, being provided at diametrically opposed 25 points with angular bayonet slots 30 having recesses 31 in their locking portions, and adapted to engage diametrically opposed lugs 32 secured to the casing. In order to connect the rim, it is fitted over the lens 30 and upon the casing, and by applying pressure to the rim the glass cylinder is pressed inwardly, compressing the rubber washers 26 and 23 and the spring member to a point 35 permitting the locking portions of the bayonet slots to be turned into engagement with the lugs 32 by rotating the rim upon the casing. The pressure thus produced effectually retains the rim locked, the lugs being seated in the recesses 31. To disconnect the rim, it is only necessary to press the same inwardly at the same time rotating it upon the casing to bring the entrance portions of the bayonet slots into line with the lugs 32.

The resilient supporting of the glass cylinder and lens is such that fracture, breakage or looseness, through constant vibration or shock is entirely prevented, and the interior of the lamp is maintained moisture and dust proof. The provision of resilient means at each end of the glass cylinder is such that the cylinder is resiliently supported longitudinally, the resilient means at one end compensating the resilient means at the other end, so that as one gives the

other follows. The lamp is of sturdy construction, is neat in appearance, and may be manufactured by economical fabricating processes.

I have illustrated and described a preferred and satisfactory embodiment of the invention, but it will be obvious that changes may be made therein, within the spirit and scope thereof, as defined in the appended claims.

Having thus described my invention, what I claim and desire to secure by Letters Patent is:

1. In a lamp, a cylindrical cup shaped casing, a lamp socket supported in the rear wall of said casing, a fragile cylinder in said casing substantially equal to the length of the casing, resilient means interposed between the inner end of said cylinder and said rear wall of the casing to cause the projection of a portion of the forward end of said cylinder forwardly of the forward edge of the casing, a lens at the forward end of the cylinder, resilient means interposed between the forward projecting end of said cylinder and said lens, a flanged rim engaged upon the forward end of said casing and over the margin of the lens, and means for securing the rim on the casing and to compress the resilient means at the rear of said cylinder, the two resilient means maintaining the rim in secured relation and compensating each other, whereby as one gives the other follows.

2. In a lamp, a cylindrical cup-shaped casing having an opening in its cylindrical portion, a lamp socket supported in the rear wall of said casing and within the lower half thereof, a transparent cylinder in said casing open at each end, a leaf spring extending across said casing above said lamp socket and having its ends interposed between the inner end of said cylinder and the rear wall of said casing, a lens at the forward end of said cylinder, a flanged rim engaged upon the forward end of said casing and over the margin of said lens, and means for securing said rim adapted in its secured position through said lens and cylinder to compress said leaf spring, whereby said cylinder is resiliently supported longitudinally.

3. In a lamp, a cylindrical cup-shaped casing having an opening in its cylindrical portion, a lamp socket supported in the rear wall of said casing and within the lower half thereof, a transparent cylinder in said casing open at each end, a leaf spring extending across said casing above said lamp socket and having its ends interposed between the inner end of said cylinder and the rear wall of said casing, the upper and lower edges of said spring being parallel and above and below the central axis

of said casing, and its ends being concentric with the cylindrical portion of said casing, a flanged rim engaged upon the forward end of said casing and over the margin of said lens, and means for securing said rim adapted in its secured position through said lens

and cylinder to compress said leaf spring, whereby said cylinder is resiliently supported longitudinally.

Signed at Bridgeport, county of Fairfield and State of Connecticut, this 8th day of June, 1923.

DANIEL H. DEERY.
